UNITED STATES PATENT OFFICE.

GEORGE F. SPROULL, OF MONTGOMERY, ALABAMA.

MACHINE FOR DISTRIBUTING POWDER OVER GROWING PLANTS.

Application filed November 18, 1920. Serial No. 424,951.

To all whom it may concern:

Be it known that I, GEORGE F. SPROULL, a citizen of the United States, residing at Montgomery, in the county of Montgomery and State of Alabama, have invented certain new and useful Improvements in Machines for Distributing Powder Over Growing Plants, of which the following is a specification.

10 My said invention consists in certain improvements in the details of construction and arrangement of parts of machines for distributing insect powder over growing plants particularly cotton plants, whereby a 15 machine of such type is provided which is very efficient in use and very convenient in operation, all as will be hereinafter more fully described and claimed.

Referring to the accompanying drawings 20 which are made a part hereof and on which similar reference characters indicate similar parts,

Figure 1 is a side elevation of a machine of the character mentioned, illustrating my 25 improvements;

Figure 2, a top or plan view of the same, and

Figure 3 a detail view on the dotted line 3—3 in Figure 1.

30 In said drawings, the portions marked A represent the frame, B the wheels, and C the hopper.

The frame A is of any appropriate construction to carry and support the various 35 parts of the mechanism. The wheels B are mounted on the axle 10 mounted in bearings on the frame as is usual.

The hopper C is designed to contain the powder which is to be distributed and has 40 an agitator 11 therein, a screw conveyor 12 in its bottom and a blower fan 13 mounted in the casing 14 on one side thereof.

To the front portion of the frame A is attached an arched member composed of 45 parts 15 and 16 connected by a member 17 to which the driving power may be attached. Said members 15 and 16 are formed with vertical perforations adjacent to the member 17, through which a post 18 extends. Said 50 post 18 has a caster wheel 19 mounted in a frame 20 swiveled on the lower end of the post for supporting the front end of the machine. Post 18 is formed with a series of circumferential grooves 21 at intervals 55 and a latch 22 pivoted on member 15 on a pivot 23 is adapted to engage by

means of a bifurcated end in one of said grooves and hold the frame in adjusted position thereon. A spring 24 interposed between a bracket 25 and the back of said latch, tends to normally hold it into engagement with one of said grooves. A connecting rod 26 connects said latch with a lever 27 pivoted at 28 on member 16, and said lever 27 is connected by a connecting rod 29 with a foot lever 30 pivoted at 31 on the rear of the frame. Handles 32 for guiding the machine are pivoted near the front end of the frame on pivots 33 and are connected to notched segments 34 by means of pawls 35 operated by levers 36 adjacent to the handles, to which they are connected by connecting rods 37. Said segments 34 are supported at their lower ends on the rear ends of the frame and at their upper ends by 75 braces 38, as shown.

Nozzles 39 are connected by pipes 40, 41, and 42 to the discharge spout of the blow fan casing 14.

A sprocket wheel 43 is loosely mounted on the axle 10 of the wheels B and connected by a sprocket chain 44 with another sprocket wheel 45 on the counter-shaft 46. A second sprocket wheel 45 on said shaft is in turn connected by another sprocket chain 47 to a sprocket wheel 48 on the blower fan shaft 50. A pinion 51 is mounted on the opposite end of blower fan shaft 50 and is connected by a gear 52 with another gear 53 on the shaft of agitator 11.

In operation, the parts being in the position shown and described and the hopper C filled with powder for distribution, the machine is driven between the rows of plants, the discharge nozzles 39 being directed to distribute the powder on a row of plants on each side of the machine. As the machine is driven across the field, the powder is thoroughly agitated and mixed by the agitator 11 and is conveyed by the conveyor 12 into the blower fan casing 14 and by the blower is discharged through the pipes and nozzles and is distributed over the plants, as will be readily understood. When it is desired to turn the machine, the operator by means of the foot lever 30, disengages the latch 22 from the post 18 and by means of the handles 32 tilts the forward end of the frame upward on the wheels B and axle 10, permitting the post 18 to slide downwardly 105 through the apertures in the members 15 and 16. When the forward end of the frame

has been sufficiently elevated, the foot lever is released and spring 24 returns latch 22 and locks the parts in this position. The operator then through levers 36 withdraws pawls 5 35, lowers the handles 40 on the segments 34 to the desired point, re-engages said handles, and then lifts the machine on the caster wheel 19, turning it free from the plants and thus moves it over to the next adjacent 10 row of plants without injury or even contact therewith. The parts are again returned to normal position and the machine drawn across part of the field desired and this operation continued until the part of the field 15 infected by insects has been treated.

A clutch 54 is mounted by means of a spline on axle 10 and adapted to engage with and be disengaged from a similar clutch on the hub of the sprocket wheel 43. A lever 20 55 formed with a shifting fork on its forward end engages with the groove in the clutch-part for effecting the shifting operation, as will be readily understood.

It will be seen that by this construction I 25 provide a machine for the purpose that may be easily guided by the handles notwithstanding it is built narrow enough to pass between the rows without contact with the plants. The machine can also be turned 30 anywhere in the field without injury to the plants and this is important as it frequently happens that only a comparatively small portion of a large field of cotton will be infected and the infected patch may be and 35 usually is right in the midst of the field. It is also of advantage for use in a field where there are stumps, as newly cleared ground, as by the construction shown, the machine can be readily manipulated around such 40 stumps without injury to the cotton plants.

Having thus fully described my said invention, what I claim as new and desire to secure by Letters Patent, is:

1. A machine of the character described

comprising a frame, a hopper on the frame, 45 a casing at one side of the hopper, a shaft extending through the casing and the hopper and having mounted thereon and adapted to be driven thereby a conveyor and a fan, said shaft also being adapted to drive 50 an agitator in the casing, substantially as set forth.

2. A machine of the character described comprising a frame, a hopper on the frame, a casing alongside the hopper, a fan in the 55 casing, an agitator in the hopper, a screw conveyor in the hopper below the agitator to convey material from the hopper to the fan casing, and means for driving the agitator from the conveyor, substantially as set 60 forth.

3. A machine of the character described comprising a frame, a hopper on the frame, a casing at one side of the hopper, a shaft extending through the casing and hopper, a 65 fan in the casing and a conveyor in the hopper secured to and driven by said shaft, an agitator in the hopper above the conveyor also driven from said shaft, driving means for the shaft connected to the supporting 70 wheels of the machine, and means for disconnecting said driving means, substantially as set forth.

4. A machine of the character described comprising a frame, a hopper on the frame, 75 parallel shafts extending through the hopper, a screw conveyor on the lower shaft, agitating plates for the material in the hopper parallel to the upper shaft and secured thereto, and gearing connecting the shafts 80 for driving one from the other, substantially as set forth.

In witness whereof, I have hereunto set my hand and seal at Washington, D. C., this 21st day of October, A. D. nineteen hundred and twenty.

GEORGE F. SPROULL. [L. S.]
